CALCULATING MACHINE

John C. Gates, Downers Grove, Ill., assignor to
 Western Electric Company, Incorporated, New
 York, N. Y., a corporation of New York

Application May 24, 1939, Serial No. 275,574

9 Claims. (Cl. 235—61.7)

This invention relates to calculating machines and more particularly to apparatus for verifying the results produced by multiplying machines and is a continuation, in part, of my co-pending application, Serial No. 83,861, filed June 6, 1936.

It is an object of the present invention to provide economical apparatus for reducing the possibility of recording incorrect results by automatic multiplying machines.

In accordance with one embodiment of the invention, as applied to multiplying machines capable of receiving therein multi-digit factors, performing a multiplication involving said factors, and recording the result of such multiplication in the form of perforations on record cards, the punching of the result produced by the multiplying machine is made dependent upon the comparison of the result of two auxiliary computations, one of which involves the digits of the factors entered into the multiplying machine and the other of which involves the digits of the product produced by the multiplying machine. The apparatus which performs the first mentioned of these auxiliary computations is operable under control of the factor entry devices of the multiplying machine and is provided with a receiving device which, simultaneously with the entry of the factors into the main multiplying machine, receives impulses representing the digits of the factors. This auxiliary receiving device, upon the entry of the digits of the factors into it, sets up circuit conditions representative of the result of adding together the digits of each factor entered and subtracting therefrom the highest possible multiple of nine. The circuits representative of the sum of the digits of the entered factors control, on the first multiplying cycle of the main multiplying machine, a computing apparatus, which, under their control, will establish circuits representative of a single digit result, which is the same as the result of multiplying the two digits and subtracting from the product the highest possible multiple of nine. The second mentioned of said auxiliary computations is performed by apparatus which includes a receiving device operable simultaneously with the left-hand components accumulator of the multiplying machine and which establishes a circuit condition representative of the result of adding together all the digits of the product produced by the multiplying machine and subtracting therefrom the highest possible multiple of nine. If pulses are transmitted to the left-hand components accumulator of the multiplying machine representative of the cor-

rect product, the circuit conditions established by the first-mentioned auxiliary computing apparatus will be continued through the second auxiliary computing apparatus to initiate the punching of the product in the record card. If the two auxiliary computing devices, at the completion of their operation, do not arrive in a position where their circuit connections represent the same number, the circuit through them will stop further operation of the machine, indicating that the multiplying machine has not produced the correct answer. Thus, by means of a verifying device, much less costly than the multiplying machine, and operable simultaneously with the multiplying machine, it is possible to check the result produced by the multiplying machine without loss of time and with a commercially practical degree of accuracy.

A complete understanding of the invention may be had from the following detailed description, when considered in conjunction with the accompanying drawings, wherein—

Figs. 1 and 1A, taken together, show a somewhat diagrammatic view of the various units of the machine and the driving mechanism therefor;

Fig. 2 is a vertical sectional view, taken through the card handling and reading section of the machine;

Figs. 3 and 3A, taken together, show a somewhat diagrammatic view of the punching section of the machine;

Fig. 21 shows a diagrammatic view illustrative of the mode of operation of the auxiliary receiving devices for the multiplier factor, multiplicand factor and product and the auxiliary computing device with their associated circuit connections;

Figs. 22A, 22B, 22C, 22D and 22E are schematic views which, when arranged vertically in the order named, show the complete circuit diagram of the machine; and

Fig. 23 shows the timing diagram of the machine.

A general description will first be given of the units and their location in the machine. The machine includes a card feed and card handling section (see Figs. 1A and 2) and the well-known successively actuated punch, of the type shown in Patent No. 1,772,186 to Lee and Phillips, which receives each card as the card emerges from the card handling section. The punch is shown in Figs. 3 and 3A and a portion of the receiving tray of the punching mechanism is shown in Fig. 2.

The registers and receiving devices are as follows: In the upper part of the machine there is provided the usual right-hand and left-hand accumulators, designated generally by the numerals 1 (RH) and 2 (LH), respectively. The usual types of equipment, as referred to hereinafter, are the equipment usual in machines of the type shown in Patents Nos. 2,088,408 to Daly et al., 1,944,665 to D. J. Oldenbloom and the patent to Lee and Phillips, referred to hereinbefore. The basic or main multiplying mechanism is the same as the mechanism shown in the Oldenbloom Patent No. 1,944,665, but the control circuits therefor are modified, as will be apparent as the description progresses, and insofar as feasible, the reference letters used in the Oldenbloom patent have been applied to the various parts common to this application and the Oldenbloom patent. In the lower part of the machine, there are two registers 3 (MP) and 4 (MC), used as multiplier and multiplicand entry receiving devices, respectively (see Fig. 1). The registers 3 (MP) and 4 (MC) have associated therewith auxiliary entry receiving devices designated multiplier and multiplicand cross-adding registers 5 (MPCA) and 6 (MCCA) located immediately above them and the accumulator 2 (LH) has associated therewith an auxiliary product receiving device designated a product cross-adding register 7 (PCT), located be-

low register 1 (RH). The lower part of the machine also includes a multiplying relay unit 8 (MPR), a cross-total multiplying relay unit 9 (CTMPR) for multiplying the sums of the cross-added factors, and a column shift and control unit 10 (CS). The usual impulse emitters, cam contact devices and impulse distributor, etc., are likewise provided.

Power is supplied to drive the mechanical parts of the apparatus by a driving motor 20 (Z), which, through a pulley arrangement 21, drives an A. C.-D. C. generator 22 and a main drive shaft 23. Suitable gearing interconnects the main drive shaft 23 with a main accumulator shaft 24 and a main register drive shaft 25. The left hand components accumulator 2 (LH) has the usual Geneva reset mechanism comprising a reset shaft 26 and gears 27, 28, 29 and 30, and Geneva gear parts 31 and 32. A shaft 43, which supports the cross element 31 of the Geneva gear, carries an internal gear 44 having meshed therewith a pinion 45 mounted on a reset shaft 46 of the right hand components accumulator 1 (RH).

A multiplicand and multiplier register reset shaft 33 is provided for resetting the multiplicand (MC) and multiplier (MP) registers in the same manner that the left-hand component accumulator 2 (LH) is reset. The reset shaft 33 has parts 34, 35, 36, 37, 38 and 39, which correspond with the parts 27, 28, 29, 30, 31 and 32, respectively, associated with the reset shaft 26. The multiplier and multiplicand cross adding registers 5 (MPCA) and 6 (MCCA) are driven from the main shaft 23 through a shaft 46—A during the entry receiving operations, and are reset to normal by a reset shaft 47 connected to the drive shaft 46—A by a Geneva train, parts 51, 50, 52 and 53, 48 and 49. Mechanism comprising product cross adding (PCT) reset shaft 54, gears 55, 56 and shaft 57 similar to shaft 46, gears 45, 44 and shaft 43, respectively, are provided for resetting the product cross adding register 7 (PCT) which is electrically connected in parallel with the left-hand accumulator 2 (LH) and is operated simultaneously with it in its accumulating operations.

Card feed and card handling unit drive

Referring to Figs. 1A and 2, the customary card feed drive is provided, which may be briefly described as follows: Shaft 24, through gearing 68, 69, 70, 71 and 72, drives a gear 73, revolvably mounted on shaft 75. Fixed to gear 73 is an element 76 of a one-revolution clutch, the complementary part of which comprises a pawl 77, carried by an arm 78 fixed to shaft 75. Gear 73, through a gear 79 fixed to gear 80, drives a train of gears 81, which, in turn, drive the card feed rolls 82. Also in train with gear 79 is a gear 83 for driving drag roll shaft 84 carrying drag rolls 85.

The usual card transfer and contact cylinder 87 is provided, driven in the following manner: Fixed on shaft 75 is a gear 88, which, through gearing 89, 90, drives a gear 91, which is fixed to the sleeve 92 revolvably mounted on shaft 75, but fixed to the card transfer and contact roll 87. The intermittently actuated feed control (FC) group of cam contact devices are driven in the following manner: A driving train is provided from gear 86, which gear is fixed to shaft 75, and which train includes gearing 100, 101 and 102, the latter gear being fixed to the cam contact shaft 103. The cams on the shaft 103, which are designated 342 (FC-2), 344, 349 (FC-6), 370

(FC-11), 477 and 520, operate similarly designated contacts as shown in the wiring diagram (Figs. 22A to 22E) at the times shown in the timing chart (Fig. 23) as will be explained more fully hereinafter. Fixed to the shaft of gear 100 are spring-pressed card feed rolls 104. Other spring-pressed card feed rolls 105 are driven by a gear 106. The card picker is driven in the customary manner by a box cam 107 fixed on shaft 75 cooperating with a follower 108, which rocks a rock shaft 112 carrying a gear sector 113, which is in engagement with the picker block 114. Upon engagement of the one revolution card feed clutch, the picker is called into action to withdraw a single card from a magazine 115 (Fig. 2) and advance the card into the bite of rolls 82, which rolls, in turn, forward the card to the card transfer and contact cylinder 87. A curved card guide is provided around the transfer and contact cylinder and the advancing card is carried around by the forward rotation of the cylinder and by the rotation of rolls 104 to traverse the card past main sensing brushes, designated 116 in Fig. 2. Also in cooperation with the card is a pivoted card lever 117, operating card lever contacts 118.

After sensing, the card is advanced by the rolls 105 and cylinder 87 between guiding members 119 and 120, and while between these members, it is advanced by drag rolls 85. The drag rolls 85 deliver the card under a guiding member 121 and ultimately the card is flipped down into the tray of the punching section of the machine. The location of the tray is indicated at 122 in Fig. 2 and the position of a card in this tray is indicated at 123 in Fig. 1a.

A card lever 124 (Fig. 2) is provided adjacent the tray for closing card lever contacts 125 when a card is in the tray. In the operation of the machine, a card, in moving past the sensing brushes 116, will cause the factors of the problem to be entered in the machine.

Multi-contact relays

The machine includes a number of electro-magnetically tripped and mechanically reset multi-contact relays. These are used in the multiplying relay unit 8 (MPR), the cross total multiplying unit 9 (CTMPR), and the column shift unit 10 (C5) sections of the machine. The mechanical reset for these relays is provided for in the following manner: The lower drive shaft 25 drives operating cams 126 (see Figs. 1a and 14). Cooperating with each cam 126 is a follower arm 127, which is adapted to rock a bail 128. Loosely mounted on a shaft 129 (Fig. 14) are a number of U-shaped members 130, each provided with an arm portion 131 extending under the bail 128 and cooperating with a latch member 132 which is pivotally mounted on an armature member 133 and spring urged in an anti-clockwise direction by a spring 134. The armature is normally rocked clockwise by a spring 135. Each member 130 has an armature knockoff arm 136 adapted to cooperate with a knockoff extension 137 of the armature. Also fixed to each member 130 is an insulated contact operating part 138, which is normally drawn to the left by a spring 139. The contacts 140 and 141 are provided, the latter (141) being fixed to the member 138. Upon the full movement of part 138 to the left, the contacts 140 and 141 will close.

In the operation of this multi-contact relay, the bail 128 is first displaced to the position shown and arm 131 is slightly depressed to relieve the

strain from the latch point where 131 cooperates with 132. A relay magnet, such as the magnet shown in Fig. 14, which has not been assigned a reference numeral since it might be any of the relays under discussion, may then be energized, swinging the armature 133 to the right, causing the latch 132 to clear 131 and snap down under spring action by spring 134 to a position at the end of member 131. Thereafter, upon further motion of the cam 126 in the direction indicated by the arrow, the bail 128 is elevated, allowing an anti-clockwise motion of member 130 and permitting the contacts to close under spring action. Subsequently, further movement of the cam 126 causes the bail 128 to be again depressed to reopen the contacts and to thrust 136 to the right to a supplemental extent to knock off any previously attracted armature. At this time, there is a relatching of the latch 132 with member 131. If a given armature is not attracted by the energization of the relay coil, latch 132 will not be tripped and such latch will prevent the anti-clockwise motion of members 130 and the closing of the contacts upon the elevation of bail 28.

In the subsequent description of the wiring diagram, certain of the contacts which have been generally designated 140 and 141 in the foregoing description of the relay, will be given designating numerals related to their associated relay control magnets. Thus, the contacts 430 are the contacts which are controlled by the relay magnet 429 in reading out the right-hand components accumulator 1 (RH) into the left-hand components accumulator 2 (LH) at the end of a problem.

Punching mechanism

The punching mechanism is of the usual successively acting repetition punching type generally used in machines of this class. It is generally of the form shown in Lee and Phillips United States Patent No. 1,772,186 and in British Patent No. 362,529.

Inasmuch as the punching mechanism illustrated herein is not of itself a part of the present invention, the description thereof will be brief and will simply outline the mode of operation generally. It is sufficient to here state that after the receipt of the card in the receiving tray 122 in the punch at the 123 position and with the punch driving motor 154 (Z2) (Figs. 3 and 3A) in operation that a rack 155 is displaced to the left to push the card from position at 123 to a position 156. Movement of the rack 155 to the left is effected by the one revolution punch clutch generally designated 157, which clutch is engaged by the energization of punch clutch magnet 158. The traverse of rack 155 to the left causes shaft 159 to rotate clockwise by means of the ratchet driving device, generally designated 160 (see also Fig. 5). The clockwise rotational movement of shaft 159 displaces rack 161 to the right to a position in which pusher fingers 162 can engage back of the trailing edge of the card at position 156. Thereafter, rack 161 moves to the left under spring power from a spring in barrel 163 and another spring drive at 164 restores rack 155 to its right hand position.

After the card has been passed through the punch, it ultimately reaches a position in which the eject mechanism 165 receives the card. Following this there is a trip of the eject mechanism by energization of eject magnet 166 and the

eject mechanism swings to the position shown in Fig. 3 to deliver the card into a discharge magazine or box, as indicated by the dotted line position of the card in Fig. 3. The box is generally designated 167. The movement of rack 161 to the left is under the influence of the usual escapement 168 and each time the card escapes a column, the escapement contacts 169 are opened.

The punching section of the machine is provided with contacts which may be briefly described. Contacts 180 (P1) are contacts which are closed when rack 155 is in the extreme right-hand position and in proper position to receive a new card from the card handling and sensing section of the machine. Contacts 181 (P2) (Fig. 3A) are contacts which are normally closed and which open when rack 155 is in its extreme left-hand position. Contacts 182 (P3) (Fig. 3) are eject contacts which open when the eject assemblage 165 is moved to card receiving position. With the eject mechanism in the position as shown, such contacts are closed. Contacts 183 (P5) (Fig. 3) are contacts which are normally open and are closed when the rack 161 and the card move beyond the last column position.

Contacts 184 (Fig. 4) are also provided, which are arranged to be closed upon energization of the punch clutch magnet 158. Such contacts are latched closed by a latch 185 and the latch is released and the contacts are allowed to open by a knockoff associated with the one revolution clutch assembly 157.

Readout devices

Referring to Figs. 6 and 7, which show the multiplier readout (MPRO) designated generally by the numeral 190, 191 is a clutch gear pertaining to the units order of the multiplier (MP) receiving device. Gear 192 is driven from this clutch gear and this gear, in turn, drives brush assemblies, designated 193 (U) and 194 (U). Brush assembly 193 (U) traverses segments 195 and current supply segment 196. Brush assembly 194 (U) traverses a segment block 197 provided with a single spot at the zero position and also traverses current supply segment 198. There is also a brush assembly 199 (T) which traverses the 197 segment and which receives current from a current supply segment 200. This brush assembly 199 (T) and a brush assembly 201 (T) are driven from the tens order clutch wheel 202. Brush assembly 201 traverses segment spots 203 and receives current from a supply segment 204. This arrangement of brushes and segments is repeated for the higher orders in the multiplier readout 190 (MPRO), i. e., each alternate segment is like 197 with only a single spot in the zero position and alternating with such segments are other segments similar to 195 and 203 with a multiplicity of spots on each segment.

The wiring of the multiplier readout 190 (MPRO) will be shown in connection with the description of the circuit diagram.

Multiplicand readout (MCRO)

The drive for the multiplicand readout brush assemblies, designated generally by the numeral 208, is the same as previously described for the multiplier readout (MPRO). The segment arrangement, however, is different. In lieu of the segments 195, 197 and 203, segments 205, 206 and 207 are provided each with a multiplicity of spots as shown, i. e., there are nine spots on each segment.

Readout for right-hand components accumulator (RHRO)

With the readout for the right-hand components accumulator 1 (RH), as designated generally by the numeral 228 (RHRO), a different arrangement is provided. The units order gear train 221 drives a brush assembly 222 (U), which traverses segments 223 and which receives current from a conducting segment 224. The tens order train 225 drives a brush assembly 226 (T) which also traverses the segments 223 and which receives current from a conducting segment 227. This arrangement is repeated for relatively higher orders of the readout.

The wiring of this readout will appear on the circuit diagram.

Readout for left-hand components accumulator (LHRO)

The readout device for the left-hand components accumulator 2 (LH), as indicated generally by the number 230, has a drive which is similar to the drive for the multiplier and multiplicand readout devices 190 (MPRO) and 208 (MCRO), respectively. The arrangement of segments is substantially the same as the multiplicand readout device 208 (MCRO) with the exception that there are ten conducting spots in the readout for the left-hand components accumulator instead of the nine in the multiplicand readout devices and only one readout brush is provided in each denominational order. The reference characters 231, 232 and 233 designate the segments of this readout device, the wiring of which will be shown in the circuit diagram.

Cross adding registers

The three cross adding registers are of similar construction and differ only as to the number of dials provided. The multiplier and multiplicand cross adding registers 5 (MPCA) and 6 (MCCA) have eight dials each. The product cross adding register 1 (PCT) consists of seventeen dials, sixteen of them being utilized for receiving the regular product of multiplication and the seventeenth for receiving the single digit result of the operation of the cross total multiplying relay (CTMPR).

In each of these units, the dials are provided with only nine positions instead of the conventional ten, and the usual tens carry mechanism is omitted. The dial positions are 0 and 1 to 8, position 9 being omitted. Thus, it is evident that the nine position dial connected in parallel with the ten position dial of the conventional register will, upon receiving an impulse timed to give an input of 9 to the regular dial, execute a complete revolution and return to normal or zero. This is the means employed for dropping nines or multiples of nines and will be explained more in detail later.

Since the three cross adding registers are of similar construction, the details of only one of them will be shown, that is, the multiplier cross adding register 5 (MPCA). The multiplier cross adding register 5 (MPCA) (Figs. 16, 17, 18, 19 and 20) comprises a rectangular frame 241 (Figs. 16 and 17) in which the register units are mounted. A drive shaft 242, driven continuously from the shaft 46—A (Fig. 1) through gears 243 and 244, extends through the frame 241 and has slidably keyed thereto driving clutch members 245.

In the multiplier cross adding register 5, there are provided eight clutch members 245, one each

for the units, tens, hundreds, thousands, ten-thousands, hundred-thousands, millions and ten-millions denominations in the multiplier. These clutches are actuated by the usual electromagnetic actuating devices controlled by the card being sensed, and are connected in parallel with the clutch actuating electromagnets in the multiplier register 3 (MP), the usual means being provided for disengaging all of the clutches simultaneously. Associated with each clutch member 245 is a 10 driven clutch member 246 having a gear 247 fixed thereto. Mounted within the frame 241 are a pair of reset gears and their associated shafts 248 and 249, which support the register units. The driving clutch members 245 have been lettered U, T, H, etc. to TM to indicate the denominational order of each clutch member. The units order (U) clutch 245 has its associated register unit mounted above it, and the tens order (T) clutch has its register unit mounted to the right and below it. This sequence is followed throughout the hundreds, thousands, ten-thousands, hundred-thousands, millions and ten-millions orders, the register units being mounted upon reset shafts 248 and 249. The register units for units, hundreds, ten-thousands and millions are mounted on the shaft 248, and the register units for tens, thousands, hundred-thousands and ten-millions are mounted on the reset shaft 249. This method of positioning the various register units is followed for the purpose of conserving space in the machine. Each register unit has a gear 250 individual thereto which meshes with its associated gear 247. Each of the register units is of the same construction as all of the others and, therefore, only one of them will be described, that is, the register unit of the tens order.

The gear 250 is provided with a plurality of pins 260-260 which cooperate with a detent roller 261 for the purpose of properly centering a register unit in any of its nine rotative positions. A bushing 262 (Figs. 18 and 20) is mounted upon and rotatable about the shaft 249 and is fixed to the gear 250. A pair of apertures 263 are formed in the gear 250 for receiving screws 264 which serve to clamp the various parts of the register unit to the gear 250. The pins 264 are provided with a head at one end and a threaded portion at the other end thereof, the head portion engaging a commutator 265, and the threaded portion engaging an end plate 266. Positioned between the commutator 265 and the gear 250 is a spacing ring 267 and at the right side (Fig. 20) of the gear 250 is a second spacing ring 268. A plurality of insulating rings 269 and a plurality of slip rings 270 are clamped between the end plate 266 and the spacer 268, the insulating rings 269 serving to insulate the slip rings one from another. A tubular insulator 271 serves to insulate the pins 264 from the slip rings 270. In Figs. 16 and 20 the slip rings have been numbered 0, 1 to 8 and conducting spots 272 on the commutator which are metallic elements embedded in the insulating material of the commutator, have been similarly numbered (see Figs. 17 and 18).

In each register unit (Figs. 17 and 18) wires 273-273 are connected from the conducting spots 272 representing the numbers 0 to 8 on the commutator 265 to terminals 275 on the slip rings representing corresponding numbers. These wires 273 pass through an aperture 274 formed in the commutator 265, spacing rings 267 and 268 and gear 250 and through the space between 70 268 and gear 250 and through the space between

the bushing 262 and the slip ring 270 and insulators 269. A pawl 280 pivoted on the commutator 265 is normally urged about its pivot in an anti-clockwise direction by a spring 282.

5 This pawl 280, when the register units are in normal position, engages a notch 281 in the shaft 249. During input cycles, the register unit may be rotated about the shaft 249 in a clockwise direction while the shaft is standing still. However, upon the initiation of the clearout operation, when the shaft is rotated in a clockwise direction, the pawl 280 will ride on the peripheral surface of the shaft until the notch in the shaft comes into engagement with the pawl, at which time the register unit will be rotated in a clockwise direction until the shaft stops, at which time the register units will all be in their zero position.

Associated with each register unit are a plurality of plates 290 secured to the rectangular frame 241 and each supporting a set of nine brushes 291 arranged around the shafts 248 and 249 adjacent each register unit. Each one of the brushes 291 will engage a conducting spot 272 on the commutator 265 when the commutator is in any of its rotated positions. These nine brushes 291 are connected, individually, by suitable wiring to a set of nine brushes 293, which engage the slip rings of the register unit of the next higher order. More specific details of the circuit connections between the various commutators and slip rings will be given in the description of the wiring diagram.

Emitters and cam contacts

The main accumulator shaft 24 (see Fig. 1) is adapted to drive the cams of certain cam contact devices. These cams are numbered 300 (CC1) 301 (CC2), 302 (CC3) and 303 (CC4) and 40 operate similarly designated contacts shown in the wiring diagrams (Figs. 22-A to 22-E at the times as indicated in the timing chart (Fig. 23). Also driven from the shaft 24 is an emitter 304, which is of conventional construction. An impulse distributor 306 is provided, which is driven in unison with the cams 300 (CC1), 301 (CC2), 302 (CC3) and 303 (CC4).

Reset control contacts

50 Referring to Fig. 1, a reset gear 386 of the left-hand components accumulator 2 (LH) is driven through a conventional single revolution clutch 387 by the shaft 26 and is provided with a cam 388 adapted upon a rest of this accumulator to cause closure of contacts 307 and to shift a three-plate contact arrangement to open contacts 309 and to close contacts 308. On the multiplicand entry receiving device 4 (MC) two contact pairs are provided; viz, contacts 311 and 312. Contact 311 is arranged to be closed upon reset of this accumulator and contact 312 is arranged to be opened upon reset of this accumulator.

65 Referring to Fig. 15, 315 are the start key contacts controlled by start key 316 and 317 are the stop key contacts controlled by the stop key 318. Intermediate the contacts there is a spring-urged latch member 319. This arrangement is such that upon the depression of the stop key 318, the latch member 319 will keep the stop key contacts 317 open and the start key contacts 315 will also be kept open. Thereafter, upon depression of the start key 316 to close the contacts 315, the latch member 319 will be rocked anti-clockwise to release the stop key contacts and to permit their reclosure.

Circuit diagram

It will be understood that the present machine is intended for the original computation and production of perforated records, and for the checking of the results before the punching of the record takes place.

In order to clarify somewhat the description of the circuit diagram and the operation thereof, a brief description in general terms of the operation will now be given. Let it be assumed that a supply of cards having factors punched therein are placed in the card supply magazine 115 and the machine set in operation. The cards will pass under the sensing brushes 116 and the multiplier and multiplicand factors will be read from each card and stored in the multiplier entry receiving device 3 (MP) and multiplicand entry receiving device 4 (MC) and will be simultaneously registered in the multiplier cross-adding register 5 (MPCA) and the multiplicand cross-adding register 6 (MCCA). As pointed out in the general statement hereinbefore, the electromagnets which control the multiplier entry receiving device 3 (MP) and the multiplier cross-adding register 5 (MPCA) are connected in parallel, and the electromagnets which control the multiplicand entry receiving device 4 (MC) and the multiplicand cross-adding register 6 (MCCA) are also in parallel. Therefore, the input in the corresponding registers will be the same.

After the cards have passed the sensing brushes 116, they then move to the position indicated at 123 (Figs. 1A and 3A) where they operate contacts for closing a circuit to transfer them to position to be worked upon by the punch. At approximately this time, a contact is made under control of the clearout of the left-hand components accumulator 2 (LH) to initiate the multiplying cycle. Upon initiation of the multiplying cycle, the impulse emitter 304 becomes effective to send impulses over the circuits closed by the operation of the multiplier relays (MPR) under control of the multiplier entry receiving device 3 (MP) through the multiplicand register 4 (MC) contacts and through the column shift (CS) relays into the right-hand and left-hand components accumulators 1 (RH) and 2 (LH), respectively. Simultaneously, and in the same manner, the check multiplier (CTMPR) relays are operated and in this case no column shift relays are required since the result transmitted by the check multiplier relays will always be one digit, which is put immediately into the check dial of the final product cross-adding register 7 (PCT), all of which will be described more in detail in connection with the operation of the circuit. After the input of the factors into the entry receiving devices 3 (MP) and 4 (MC) and the initiation of the multiplying cycles, normal multiplication proceeds under control of the stored factor and column shift relays until the last active digit in the multiplier factor is effective, all of which will also be described more in detail in connection with the operation of the machine. After the last multiplier digit is effective, the left-hand components accumulator 2 (LH) will have transferred thereto the amount standing in the right-hand components accumulator 1 (RH).

It should be understood that the product cross-adding register 1 (PCT) receives the two sets of impulses just mentioned simultaneously with the receipt of these impulses by the left-hand components accumulator 2 (LH); that is, the impulses from the multiplier relays and the

5 impulses from the right-hand components accumulator 1 (RH). The product cross-adding register 1 (PCT) will at this time have received the product of the cross-total multiplying relay 8 (CTMPR) and if the cross-added product agrees with the product produced by the cross-total multiplying relays 8 (CTMPR), a circuit will be completed to actuate the punch. If, however, the two products produced do not agree, the interposer bar magnets of the punches will be shunted to render them inoperative and the card will be moved through the punch without punching, whereupon the entire machine will stop.

10 In setting the machine into operation, the cards are placed in the card magazine of the machine and the operator then closes the main switch 320, providing current supply for the main driving motor 20 (Z). The main motor drives the A. C.-D. C. generator 22 (Fig. 1) and supplies direct current to leads 321 and 322 (Fig. 22E) and alternating current impulses to the lead 323 and to ground.

15 The multiplier and multiplicand entry circuits are plugged up in the usual way; that is, plug connections are made in certain of plug sockets 324 which are connected to the main sensing brushes 116 and to plug sockets 325. One set of such plug connections 325 are provided for the multiplier connections, and one set are provided for the multiplicand connections to direct the entries received by the brushes 116 to control magnets 326 in the multiplicand entry receiving devices 4 (MC) and the control magnets 327 in the multiplier entry receiving devices 3 (MP). Connected in parallel with the control magnets 326 and 327 are control magnets 328 and 329, respectively, of the multiplicand cross-adding register 6 (MCCA) and 5 (MPCA), respectively.

20 Having plugged up the machine in the manner above explained, the operator depresses the start key 316 to close the start key contacts 315 (Fig. 22E). Closure of these contacts completes a circuit from lead 322, through relay coil 340 (C), relay contacts 341 (G-1), now closed, and through cam contacts 342 (FC-2) to lead 321. A locking circuit is established through the contacts 343 (C-2) of relay 340 and through cam contacts 344 (FC-8) now closed. Energization of coil 340 (C) also closes contacts 345 (C-1) and a circuit is established to energize a card feed clutch magnet 346 (see also Fig. 1A). This circuit is completed from the lead 322 connected to the DC line through contacts 347 (F-1) of a relay 348 (F) now in the position shown in Fig. 22E through the card feed clutch magnet 346 through cam contacts 349 (FC-6), now closed, through stop key contacts 317, now closed, through contacts 350 (N-1) of relay 351 (N) and contacts 345 (C-1) of relay 340 (C), now energized, through contacts 180 (P-1) of the punch, now closed, to the other side of the DC line through lead 321.

25 The start key 316 is held depressed until after the second card feed cycle is initiated and until after card lever contacts 118 are closed, causing energization of relay 352 (H). Energization of relay 352 (H) closes its contacts 353 (H-1) (Fig. 22E). As the second card feed cycle ensues, the card is carried past the brushes 116 and the amounts of the multiplier and multiplicand are read from the card and entered into the multiplicand and multiplier entry receiving devices 4 (MC) and 3 (MP) and simultaneously into the multiplier and multiplicand cross-adding registers 5 (MPCA) and 6 (MCCA). The entry cir-

cuits into the entry receiving devices need not be traced in detail since this is the usual method of entering amounts into entry receiving devices. It will be understood that since the control magnets 327 and 329 are in parallel and the control magnets 326 and 328 are also in parallel, the same input impulses entered into the entry receiving devices will be entered into the corresponding cross-adding registers, although, as will be explained, these devices will not necessarily register the same numbers at conclusion of the input.

Upon the entry of an amount into the cross-adding registers 5 (MPCA) and 6 (MCCA), these registers will automatically cross-add the digits dropping from the result 9 and multiples of 9. This is accomplished in the following manner: As pointed out in connection with the description of the structural features of the cross-adding registers, each register unit has nine rotative positions 0 and 1 to 8 and no carry circuits are provided. It will be apparent, therefore, that if, for example, the digit 9 is entered into any register unit, that register unit will go through one complete cycle and return to its normal or zero position, and if no entry is made into a given register unit, the register will simply stand in the zero position. In this manner 9's are eliminated in the cross-totalling operation. If, by way of example, the digits 8 and 5 are entered into the units and tens orders and no digits are entered into the hundreds, thousands, ten-thousands, hundred-thousands, millions and ten-millions orders, respectively, of the multiplier cross-adding register 5 (MPCA), the units order register unit will rotate through eight positions, the tens order will rotate through five positions and the hundreds order to the ten-millions order will remain in zero position.

Referring to Fig. 22A and considering it in conjunction with Fig. 21 wherein the lead indicated by the numeral 360 is shown connected to the brush 291 for zero in the ten-millions order register unit and the register elements being shown in normal position, the lead 360 would be connected through the brush 291 for zero position, the contact 272 in the zero position, the wire 273 connecting the contact 272 and the zero slip ring 270, brush 293 connected directly to the brush 291 for zero in the next lower order (see also Figs. 16 to 20). Now, it having been assumed that digits 8 and 5 have been put into the units and tens orders of the multiplier cross-adding register 5 (MPCA), respectively, and all the other orders are standing in their zero positions, the tracing of the circuit from lead 360 through a typical register of this type is as shown by the heavy line in Fig. 21. Following this circuit, the lead 360 in the ten-millions (TM) order connects normally to zero, and with the register unit for the ten-millions (TM) order, the register unit for the millions (M) order, the register unit for the hundred-thousands (HT) order, the register unit for the ten-thousands (TT) order, the register unit for the thousands (TH) order and the register unit for the hundreds (H) order in their zero position, the lead 360 will be connected through those orders to the zero brush 291 in the register unit for the tens order. Register unit for the tens order has moved ahead to position 5 and lead 360 is extended through register units (TM), (M), (HT), (TT), (TH), (H) and (T) through brush 293 for the digit 5 to what would be position 5 of register unit (U) if register unit (U) were in normal position. Register unit (U) has moved

through 8 positions and therefore lead 360 will be extended through all of the orders of register units to the brush 293 for the digit 4 of the register unit (U). In this manner, the lead 360 is extended at the time of the original input, through the register units of the register.

Completion of the analysis above shows that the final destination of lead 360 is the number 4 cross-total multiplying relay 422 (CTMPR) and indicates that the sum of the digits of the multiplier with nines cast out is 4. Thus the multiplier cross-adding register 5 (MPCA) serves to perform the function of eliminating the highest multiple of nine from the sum of the digits, as indicated by the fact that the sum of the digits selected is 13 and 13 minus 9 is 4, the result produced by the register.

In the cross-adding registers, the brushes 291, as pointed out hereinbefore, are connected through suitable wiring to the slip rings 270 in the next higher order. This system is followed throughout the registers except that the multiplier cross-adding register 5 (MPCA) (Fig. 22A) has the brush 291 in the ten-millions order normally associated with the zero contact 272 connected to a lead 360, and the other brushes 291 in that order are not connected to any wire. The brushes 293 of the multiplier cross-adding register 5 (MPCA) for the lowest order are connected to the cross-total multiplying relays 422 so that the digit 4 will be the multiplier for controlling the cross-total multiplying relay unit 9 (CTMPR).

To continue the example which assumed that the number 58 was stored in the multiplier cross-adding register 5 (MPCA) and, of course, was simultaneously entered in the multiplier register 3 (MP) or multiplier entry receiving device, let it be assumed that the number 467 is entered in the multiplicand entry receiving device or multiplicand register 4 (MC) and simultaneously in the multiplicand cross-adding register 6 (MCCA). The entry receiving devices will operate in the usual manner and the multiplicand cross-adding register 6 (MCCA) will have the digits 7, 6 and 4 entered in the units, tens and hundreds orders, respectively, and the thousands to ten-millions orders will remain in normal or zero position. In the manner described hereinbefore in connection with the multiplier cross-adding register 5 (MPCA), the lead connected to the zero brush 291, which, in the multiplicand cross-adding register 6 (MCCA), is the lead 364, will be connected through the ten millions, millions, hundred thousands, ten-thousands and thousands orders to the brush 291 for zero in the hundreds order. The register unit for the hundreds order (H) having moved ahead four places, its zero brush 291 will be connected through the register unit brush 293 for digit 4 to brush 291 in what would be position 4 of register unit (T). The register unit for the tens order has moved ahead six positions and therefore the connection from lead 364 will be continued through the tens order to what would be position 1 of the units order if the units order were in normal position. The register unit for the units order has, however, moved to position 7 and therefore lead 364 will be connected through all of the orders of the register to the brush 293 for the digit 8. The leads from the brushes 293 in the units order are connected to the contacts of the cross total multiplying relay unit 9 (CTMPR) so that the digit 8 will be the multiplicand for controlling the cross-total multiplying relay unit 9 (CTMPR).

It having been assumed that the factors to be multiplied together are 467 and 58, it will be assumed that a card having the number 467 punched therein in the area associated with the sensing brushes 116 for the multiplicand and the number 58 punched therein in the area associated with the sensing brushes 116 for multiplier, has moved past brushes 116, this will result in the multiplier and multiplicand entry receiving devices 3 (MP) and 4 (MC) having digits stored in them in the following order:

MC	MP
H T U	T U
4 6 7	5 8

Similar entries will be made in the multiplicand and multiplier cross-adding registers and the circuit connections through said registers will represent the sum of the digits cross-added with the nines cast out, as indicated graphically below:

MC	MP
H T U	T U
4; 6; 7=8	5; 8=4

The sum of 4+6+7 is 17, and since 9 is the highest multiple of 9 which may be subtracted from 17, the multiplicand cross-adding register 6 (MCCA) will establish a circuit representative of the digit 8. In like manner, the multiplier cross-adding register 5 (MPCA) will establish a circuit representative of the digit 4.

The problem just outlined may be graphically expressed as follows:

	Main mult. mech.		Auxiliary computations	
	L. H. Comp.	R. H. Comp.	T T H T U	
	TTHTU TH	TTHTU TH	T H	
Multiplicand	467	467	MCCA	4; 7=8
Multiplier	58	58	MPCA	5; 8=4
1st input cycle	03450	00286		0 3 4 5 0 -3 5
1st prelim. total	03450	00286		0 3 4 5 0 -3
1st carry	00000	00000		
1st total	03450	00286	Product	0 3 4 5 0 -3
2nd input cycle	23300	00050		2 3 3 0 0 -8
2nd prelim. total	20750	00286	Cross-add.	2 6 7 5 0 -2
2nd carry	00000	00100	Reg. (PCT)	2 6 7 5 0 -2
2nd total	26750	00336		0 0 3 3 6 -3
Trans. R.H. to L.H.	00336			2 6 1 8 6 -5
Prelim. total	26086			
Carry	01000			
Final total	27086			

It will be noted that in transferring the R. H. component into the L. H. component register, the product cross-adding register 7 (PCT) had digits added to the digits stored in its hundreds order, which caused the register wheel in that order to pass through the zero position. No carry was made and the unit in that order registered one instead of zero. In this manner, nine was eliminated from the total expressed by the product cross-adding register 7 (PCT) automatically and its final position does not correspond with the reading on the left hand components accumulator 2 (LH).

The product cross-adding register 7 (PCT) operates on exactly the same principle as the other cross-adding registers and by reference to the graphic illustration just given, it will be noted that the product cross-adding register has, at the completion of the problem, the digits 6, 8, 1, 6 and 2 in its units, tens, hundreds, thousands and ten-thousands orders, respectively, and that nothing went into the higher orders. The register units

for the hundred thousands to quadrillions orders will, therefore, be in zero position and the circuit from the zero brush 291, which is the only brush 291 in the quadrillions order, will be connected through the register units for quadrillions, hundred-trillions, ten-trillions, trillions, hundred-billions, ten-billions, billions, hundred-millions, ten-millions, millions, hundred thousands to the zero brush 291 of the ten-thousands order register unit. The ten-thousands order register unit has moved two places and therefore its brush 293 for the digit 2 will continue the circuit to the brush 291 of the thousands order for the digit 2. The thousands order register unit has moved six places and therefore its brush 291 for the digit 2 is now connected through the register unit to the brush 293 for the digit 8. The brush 293 for the digit 8 in the thousands order is connected to the brush 291 for the digit 8 in the hundreds order and since the hundreds order register unit has moved forward ten places and is now in its one position, the brush 291 for the digit 8 in the hundreds order register unit will be connected through the register unit to the brush 293 for zero in the hundreds order. The brush 293 for zero in the hundreds order is connected to the corresponding brush 291 in the tens order and since the tens order register unit has advanced eight positions, the circuit will be continued to the brush 291 for the digit 8 in the units order register unit. The units order register unit has advanced six positions and, accordingly, the circuit will be continued through the

units order register unit to the brush 293 for the digit 5.

At the completion of the illustrated problem, the product cross-adding register's circuit will represent "5", the same result produced by the cross-total multiplying relay unit 9 (CTMPR) in a manner to be described hereinafter and therefore punching of the card will proceed.

By reference to Fig. 21, it will be apparent that with the problem assumed, the circuit from the lead 360 will be connected through the multiplier cross-adding register 5 (MPCA) through the brush 293 for the digit 4 to the cross-total multiplying relay 9 (CTMPR) for the digit 4; the circuit from the lead 364 will be connected through the multiplicand cross-adding register 6 (MCCA) and the brush 293 for the digit 8 to the contacts of the cross-total multiplying relay 9 (CTMPR), and the circuit from the lead connected to the contact 475 will be connected through the product cross-adding register 7 (PCT) and brush 293 for the digit 5 to the brush

293 of the register unit associated with the cross-total multiplying relay 9 (CTMPR). It will be assumed that, as will be described hereinafter, the cross-total multiplying relay 9 (CTMPR) has advanced its cross-adding register unit five places, in which case the circuit from its brush 293 for the digit 5 will be connected through the register unit to the brush 291 for zero. The circuits just described will be effective to initiate punching of the product in the card if the result produced by the cross-total multiplying relays agrees with the result produced by the product cross-adding register 7 (PCT). However, if the results thus produced do not agree, the punch interposer magnets will be rendered ineffective and the machine will be stopped, as will be more fully explained hereinafter.

While there is a manual starting of the card feed for initial card handling cycles, on subsequent cycles the card feed is automatically initiated. Provision is accordingly made to cut off the hand initiating control after the initial card handling operations. Early in the second card feed cycle cam contacts 370 (FC-11), associated with similarly designated cams, close to energize relay coil 371 (G) over a circuit from lead 321 through card lever contacts 118, cam contacts 370 (FC-11), coil 371 (G) to lead 322. Energization of relay coil 371 (G) shifts contacts 341 (G-1) to reverse position from that shown, interrupting the circuit to the start key contacts 315, but maintaining the circuit to cam contacts 342 (FC-2). The energization of coil 371 (G) will also close relay contacts 372 (G-2) and establish a locking circuit for relay coils 352 (H) and 371 (G) either through the cam contacts 342 (FC-2) or card lever contacts 118 and cam contacts 370 (FC-11). The making time of cam contacts 342 (FC) overlaps the time when the card lever contacts 118 are open between cards. The first card, after being fed through the card handling and sensing section of the machine, ultimately passes to the position shown at 123 in the punch, closing card lever contacts 125, energizing relay coil 348 (F) causing the shift of relay contacts 347 (F-1) to reverse position from that shown.

On starting up the machine, contacts 180 (P-1), 182 (P-3), and 183 (P-5) in the punch are closed. With contacts 183 (P-5) closed, relay coil 373 (K) will be energized and relay contacts 374 (K-1) closed. Upon the shifting of contacts 347 (F-1) and upon the closure of cam contacts 302 (CC-3), a circuit will be established to punch clutch magnet 158. This circuit is completed to the other side of the line through the punch contacts 182 (P-3), now closed, and contacts 374 (K-1), which are also closed. The energization of the punch clutch magnet 158 will actuate a one revolution clutch to drive the punch through one cycle, as described in the patent to Oldenboom No. 1,944,665.

Initiation of multiplication

In the present machine on multiplying operations, the setup of the cycle controller is initiated by the reset of the left-hand components accumulator 2 (LH). The energization of relays 348 (F) and 373 (K) in the manner previously explained, cause closure of contacts 375 (F-2) and 376 (K-2) (Fig. 22E). Upon closure of the cam contacts 301 (CC-2), current flows from the 323 side of the line through contacts 301 (CC-2), now closed, through contacts 376 (K-2) and relay contacts 377 (L-2) of relay 75

378, now closed, through contacts 375 (F-2), now closed, through reset magnets 379 (LH) and 380 (PCT), in the left-hand components accumulator 2 (LH) and the product cross-adding register 7 (PCT) (see also Figs. 1 and 1A) and back to ground. The energization of the reset magnet 379 (LH) initiates the reset of the left-hand components accumulator 2 (LH), and the energization of the reset magnet 380 initiates the reset of the product cross-adding register 7 (PCT). Reset of the left-hand components accumulator 2 (LH) occurs with the racks in the punch in their extreme outer positions.

During the reset of the left-hand components accumulator 2 (LH), the reset control contacts 308 (Fig. 22E) close and energize relay coil 378 (L). Energization of relay 378 (L) opens relay contacts 377 (L-2), preventing a repetition of reset. Although relay 378 (L) is only temporarily energized by the closure of contacts 308, a locking circuit is established for this coil through contacts 381 which close upon the energization of relay 378 (L). The locking circuit is completed through the punch contacts 181 (P-2), now closed. The cycle controller is set up in the following manner: Upon the reset of the left-hand components accumulator 2 (LH), a circuit is established, traced as follows (see Fig. 22E): From the 321 side of the DC line through the reset contacts 307 of the left-hand components accumulator 2 (LH), through relay coils 351 (N) and 382 (M) and back to the other side 322 of the DC line. The energization of relay coil 382 (M) closes relay contacts 383 (M-1) and 384 (M-2), and the latter contacts establish a locking circuit for the relay coils 382 (M) and 351 (N) through the multiplicand reset contacts 312, which are now closed. Contact 383 (M-1), closed, allows AC to flow from lead 323, through contacts 301 (CC-2), contacts 383 (M-1) on Fig. 22E to break spring of contacts 398 on coil 392 (YU) through coil 396 (CSU) through multiplier units order connector bar 411 through contacts down through leads, generally designated 400, through coils 401 (X) of multiplier relays to ground.

Through the reset of the left-hand components accumulator 2 (LH), a second circuit is also established by closure of contact 412 (LH) from lead 321, contact 412 (LH) through relay coil 421 (D) to lead 322, energizing relay 421 (D) and closing contacts 361 (D). A locking circuit is provided for this coil through contacts 413 (D-2) to cam contacts 300 (CC-1).

Column skip and cycle control

The column skip and cycle control are of the usual type and it is sufficient to here state that if any brush 390 of the multiplier readout (IMPRO), indicated generally by the number 391 (Fig. 22A), stands upon a zero spot, the corresponding relay 392 (Y) of the cycle controller will be energized. Current will flow in from the DC line 321 (Fig. 22E) through the reset contacts 312, through the relay contacts 384 (M-2), now closed, the wire 393 through the zero spots of the multiplier readout device, then via the corresponding brush or brushes 390 standing on the zero spot or spots, then through the respective circuits (shown) and back to the 322 side of the DC line. Also connected to one side of the relay contacts 384 (M-2) (Fig. 22E) are the contacts 395 of column shift relays 396 (CS) for units to ten-millions orders in the cycle controller. The other side of each of these contacts

is wired back to the relay coils 392 (Y), and therethrough to the other side of the DC line at 322. Accordingly, when any relay coil 392 (Y) is energized due to a brush 390 standing on a zero spot in its corresponding column, the energization of that particular relay 392 (Y) will close its associated contact 397 (Y-1) and this relay will remain energized. Assuming that no zero appears in the units column of the amount upon the multiplier entry receiving device 3 (MP), but that zeros appear in the tens and hundreds columns and that a significant digit appears in the thousands column, there will be an energization of relays 392 (Y) in the hundreds and tens columns which will shift transfer contacts 398 to reverse position. Contact 398 in the units column will not have been shifted because its corresponding coil 392 (YU) had not been energized. Contact 398 of the thousands column will also not have been shifted. The machine is now ready to multiply by the amount of the units of the multiplier entry receiving device 3 (MP). Initiation of normal multiplication and check multiplication is effected in the following manner, and reference should be had to the problem illustrated in Fig. 21:

The energization of the relay coil 382 (M) (Fig. 22E) closes relay contacts 383 (M-1). Following the setting up of the cycle controller, cam contacts 301 (CC-2) close and current flows through these contacts, through contacts 383 (M-1), now closed, through the transfer contacts 398 of relay 392 (YU) in the units order in the position shown, down through the relay 396 (CSU) in the units order and out via the brush 390, which is standing on the "8" spot of the multiplier readout 391 (MPRO) in the units order down through the eighth line of the group of wires, designated generally by the numeral 400, to a relay coil 401 for the digit 8 in the multiplying relay unit 8 (MPR) (see Fig. 22B). There is a concurrent energization of the relay 396 (CSU) in the units order and the relay 401 for the digit 8 in the multiplying relay unit 8 (MPR). Energization of the relay 401 in the multiplying relay unit (MPR) selects the proper impulses for multiplication by 8, and the energization of the relay 396 (CSU) in the units order directs the entries in the proper columnar orders of the right-hand and left-hand components accumulators 1 (RH) and 2 (LH), respectively. Extra control contacts 395 are provided controlled by the relay 396 (CSU), and the closure of these extra control contacts, which takes place as an incident to the flow of current to the relay 401 for the digit 8 through the relay 396 (CSU), causes the energization of the relay 392 (Y) in the units order, which relay coil was not previously energized because its corresponding readout brush did not stand on a zero spot.

The energization of the relay 392 (Y) in the units order then shifts its contacts 397 and transfer contacts 398 so that upon the succeeding multiplication by the next significant figure the current flowing in through the contacts 301 (CC-2) and 383 (M-1) will be diverted by the contact 398 in the units order over to the set of transfer contacts 398 in the tens order which are in the position shown. These contacts 398 in the tens order will not have been shifted since their corresponding brush did not stand upon a zero spot. The next multiplying current impulse then flows through the contact 383 (M-1) through the contacts 398 in the tens order, and through the relay coil 396 (CS) in the tens order

over the brush 390 in the tens order of the multiplier readout to the particular wire 400, say the fifth wire, and down through the relay coil 401 for the digit 5 and out to ground upon closure of cam contacts 301 (CC-2). This current flow will effect a concurrent energization of the relay coil 401 for the digit 5, and the relay 396 (CS) in the tens order, and there will be a proper entry of the partial products amounts into the proper orders of the left-hand and right-hand component accumulators 1 (RH) and 2 (LH) at the tens position therein.

The flow of impulses for entering further partial products need not be described in detail. It is sufficient to state that upon the energization of a relay coil 401 in the multiplying relay unit 8, that the related contacts shown on Fig. 22B are closed and at the proper time in the operation of the machine current impulses flow through the emitter 304 through the multiplying relays contacts. Such impulses flow through the lines, generally designated 402, to the left-hand and right-hand sections of the multiplicand readout 208 (MCRO). The multiplicand readout device allows selected impulses to flow over the left-hand component lines designated 404 (LH), and the right-hand component lines designated 405 (RH). These last-mentioned lines extend down through the various contacts of the column shift relays 396 (CS), (the wiring being as shown in Fig. 22C for the relay contacts and the coils for the relays being shown in Fig. 22A), and the other side of the contacts of these column shift relays connect to left-hand and right-hand lines 406 (LH) and 407 (RH), which, respectively, extend to the accumulator magnets 408 (LH) and 409 (RH) pertaining to the left-hand and right-hand components accumulators 1 (LH) and 2 (RH), respectively.

The lines 406 (LH), extending to the magnets 408 (LH) in the left-hand components accumulators 1 (LH), are also connected in parallel to control magnets 420 in the product cross-adding register 7 (PCT) so that any impulse directed to the accumulator magnets for the left-hand component will also be directed to the control magnets 420 of the product cross-adding register 7 (PCT).

Concurrently with the multiplication of the digits in the multiplicand by the first significant digit in the multiplier, a multiplication will be effected which involves the two digits which were determined to be the sums of the multiplier and multiplicand digits with 9's and multiples of 9's cancelled from the total. This operation takes place in the cross-total multiplying unit 9 (CTMPR). As described hereinbefore, the multiplier cross-adding register 5 (MPCA), after having had the multiplier factor transmitted thereto simultaneously with the transmission of the multiplier factor to the multiplier entry receiving device 3 (MP), will be set to complete a circuit from the zero brush 291 in the ten-millions order through its register units to a brush 293 representative of the digit which is the sum of the digits of the multiplier factor less 9 and multiples of 9. Current will be directed over lead 360 and through the multiplier cross-adding register units to any one of the eight leads associated with the brushes 293 in the units order, depending upon the digits of the multiplier factor, as hereinafter explained. The lead 360 is connected to contact 361 (D) of a relay 421 (D), and upon closure of cam contact 301 (CC-2) the 323 side of the A. C. current will

be connected through the contact 361 (D) through the lead 360, and out over one of the leads associated with the brushes 293 in the units order to a selected one of a group of check multiplier relays 422 in the cross-total multiplying unit 9 (CTMPR), which relays are similar to the relays 401. The current impulses transmitted over the contacts of the relays 422 originate at the impulse emitter 304 and these impulses will be directed through the contacts of the operated relay 422 to all of the brushes 293 in the multiplicand cross-adding register 6 (MCCA). The impulse selected by the position of the dials of this register will determine the impulse passed on to magnet 365. Upon conclusion of one problem of multiplication, contacts 412 (LH), associated with the L. H. reset, close momentarily to operate relay 421 (D), which locks operated through contacts 300 (CC-1) to lead 321. Shortly after relay 421 (D) operates, contacts 301 (CC-2) close for a relatively short time to energize the selected relay 401 and the selected relay 422. The selected relay 422 will be operated only once for each complete problem since relay 421 (D) is energized only by the reset of the L. H. components register and the L. H. components register is reset only at the end of a problem. The relay 421 will have its locking path through contacts 300 (CC-1) made and opened once for each machine cycle, but since the relay must be originally energized over contacts 412 (LH), which close only once for each problem, only one computation will be effected by the cross-total multiplying unit 9 (CTMPR) for each problem.

It should be noted at this time that the contacts of the relays 422 are not connected in identically the same manner as are the contacts of the relays 401. The interconnection of the contacts of the relays 422 are such that, rather than sending out a right and left-hand component for each multiplication effected by the cross-total multiplying unit 9 (CTMPR), a result is sent out over the lines leading to the brushes 293 in the multiplicand cross-adding register 6 (MCCA) which is representative of the sum of the digits constituting the result of the multiplication of the cross-added factors with 9's and multiples of 9 subtracted therefrom. The following table shows the answers produced in multiplying the various digits representative of the cross-added multiplier and multiplicand:

1×1=1	3×1=3	5×1=5	7×1=7
1×2=2	3×2=6	5×2=1	7×2=5
1×3=3	3×3=0	5×3=6	7×3=3
1×4=4	3×4=3	5×4=2	7×4=1
1×5=5	3×5=6	5×5=7	7×5=8
1×6=6	3×6=0	5×6=3	7×6=6
1×7=7	3×7=3	5×7=8	7×7=4
1×8=8	3×8=6	5×8=4	7×8=2
2×1=2	4×1=4	6×1=6	8×1=8
2×2=4	4×2=8	6×2=3	8×2=7
2×3=6	4×3=3	6×3=0	8×3=6
2×4=8	4×4=7	6×4=6	8×4=5
2×5=1	4×5=2	6×5=3	8×5=4
2×6=3	4×6=6	6×6=0	8×6=3
2×7=5	4×7=1	6×7=6	8×7=2
2×8=7	4×8=5	6×8=3	8×8=1

It will be noted that, for example, $3 \times 3 = 0$ in this chart, since $3 \times 3 = 9$, and 9 should be dropped in performing the desired function. It should also be noted that in multiplying 8×6 a result of 3 is produced, or in other words, 8×6 being 48, and the highest multiple of 9 in 48 being 45,

the difference is 3. In every other respect the multiplication effected by the cross-total multiplying unit is the same as ordinary multiplication and the impulses which, for example, would be directed through the relay 422 for the digit 4 will travel through the contacts of the relay 422 for the digit 4 over the lines 403 (LH) connected to the brushes 293 in the multiplicand cross-adding register 6 (MCCA), and through the cross-adding register to the brush 291 associated with lead 364 in the ten-millions order and over lead 364 to a control magnet 365 which controls the movement of an extra register unit in the product cross-adding register.

After the normal multiplication is completed, the transfer circuits in the cycle controller will all be operated so that there will be an ultimate circuit path from the 323 side of the A. C. line through cam contact 301 (CC-2), contacts 383 (M-1) of relay 382 (M), through all of the shifted transfer contacts 398 through reset magnets 425, 426, 427 and 428 for the multiplier and multiplicand entry receiving devices 3 (MP) and 4 (MC), and for the multiplier and multiplicand cross-adding registers 5 (MPCA) and 6 (MCCA). Energization of these relays initiates the resetting of the multiplier and multiplicand entry receiving devices and the multiplier and multiplicand cross-adding registers. Connected in parallel with the reset magnets 425, 426, 427 and 428 is a transfer relay 429 (ICR) which is energized simultaneously with the reset magnets, and upon energization brings about a closure of its related contacts 430 (ICR-1 to 16), shown in Fig. 22C, and a contact 431 (ICR-17) (Fig. 22B.)

Closure of the contacts 430 (ICR-1 to 16) connects the right-hand components readout, designated generally by the numeral 432 (RHRO) with the lines 406 (LH). Accordingly, upon the operation of the emitter 304 impulses are emitted through a group of lines 433 (Figs. 22B and 22C), through the contacts 430 (ICR-1 to 16) to the accumulator magnets 408 (LH) of the left-hand components accumulator, and to the control magnets 420 of the product cross-total register 7 (PCT). The amount which previously stood on the right-hand components accumulator is, therefore, entered into the left-hand components accumulator and in the products cross-total accumulator in proper columnar relation therein. After the transfer is complete, the emitter brush of emitter 304, on encountering the extra stop thereon, supplies current through the contacts 431 (ICR-17), now closed, to a reset magnet 434 (RH) for the right-hand components accumulator 1 (RH). Energization of this magnet initiates reset of the right-hand components accumulator.

The reset of the multiplicand and multiplier entry receiving devices 4 (MC) and 3 (MP) and of the multiplier and multiplicand cross-adding registers 5 (MPCA) and 6 (MCCA) occurs concurrently with the transfer from the right-hand components accumulator 1 (RH) to the left-hand components accumulator 2 (LH), and the reset of the multiplicand entry receiving device opens contacts 312 (see Figs. 1 and 22E). The opening of such contacts breaks the locking circuit for relay coils 351 (N) and 382 (M) and for all of the relays 392 (Y), thus preparing the cycle controller for a new entry from the following cards. The result of the multiplication is now set in the left-hand components accumulator 2 (LH), and since the accumulator magnets in this accumulator are in parallel with the control mag-

nets in the product cross-adding register 7 (PCT), the product cross-adding register 7 (PCT) will have added the digits of the product and will indicate by its circuit connections the result of such addition with 9's and multiples thereof subtracted from the total.

The extra register unit associated with the electromagnet 365 in the product cross-adding register 7 (PCT) will have a single digit stored therein, which is representative of the multiplied factors cross-added with 9's and multiples of 9's subtracted therefrom. The connections in the product cross-adding register are the same as those in the multiplier and multiplicand cross-adding registers, except that the lowest order of the product cross-adding register has the brushes 293 associated with each slip ring 270 connected through suitable wiring to brushes 293 associated with the slip rings 270 of the cross-adding register unit for the electromagnet 365. The cross-adding register unit associated with the electromagnet 365 is of the same construction as the other cross-adding register units except that it has its contacts 272 for the digits 1 to 8 strapped together.

Through the setting of the cross-adding register units in the product cross-adding register 7 (PCT) and the cross-adding register unit associated with the electromagnet 365, the results of the two multiplications, with the nines cast out, are compared. This operation is graphically illustrated in the diagram shown in Fig. 21, wherein there has been shown the ten-thousands, thousands, hundreds, tens and units order units of the product cross-adding register 7 (PCT) together with the three lower orders of the multiplicand cross-adding register 6 (MCCA), the two lower orders of the multiplier cross-adding register 5 (MCPA) and the register unit associated with the electromagnet 365. The remaining orders of the registers have not been shown since the circuits in the upper orders are identical, registering zero in the selected computation, and it would only complicate the showing to show the circuit through them.

If the two results obtained agree, i. e., the result of the ordinary multiplication with the nines cast out and the result of the multiplication of the cross-added factors with the nines cast out, the register unit associated with the relay magnet 365 will be rotated to a position indicating a number which is equivalent of the number representative of the cross-adding of the digits of the product. When this occurs, the circuit through the product cross-adding register 7 from the "0" brush 291 of the quadrillion order (Q) will be continued through the "0" brush of the register unit associated with the relay magnet 365. When the results obtained do not agree, the circuit from the "0" brush 291 in the quadrillions order (Q) will be connected to one of the brushes 291 for the digits 1 to 8 in the register unit associated with the relay magnet 365. The "0" brush 291 in the quadrillions order (Q) of the product cross-adding register 7 is connected through contacts 475 (B-1) of a relay 476 (B), now closed, to lead 321. The relay 476 (B) is at this time energized over a circuit originally from lead 321 through cam contact 477 (FC-4), operated when a card passes under the sensing brushes 116 and held operated by a locking circuit through its contacts 478 and contacts 309 (LH), now closed.

The zero brush 291 associated with the register unit operated under control of relay magnet

365 is connected through the escapement contact 169 through line 6, through the punch distributor brush (Fig. 22D), through the LHRO, through the interposer magnets in the punch to effect punching in the usual manner, the circuit being completed from the interposer magnets in the punch through line 8 and through a contact 479 of relay 480, which will not be energized when the product produced by the cross-addition of a normal multiplication agrees with the product produced by multiplying the cross-added factors. The punching will then proceed in the usual manner until all of the digits of the result have been punched in the card, whereupon card feed will be reinstated to start another multiplying cycle over contacts 180 (P-1), contacts 345 (C-1), contacts 350 (N-1), contacts 317, contacts 346 (FC-6), card feed clutch magnet 346 and contacts 347 (F-1), all closed at this time.

The brush 291 associated with the digits 1 to 8 of the register unit operated under control of the relay magnet 365, is connected to the winding of the relay 480 so that the circuit through the product cross-adding register from line 321 through contact 475 (B-1) of relay 476 (B) will, when the cross-added products which are compared, do not agree, operate the relay 480 to open the contacts 479 thereof, thereby disconnecting the interposer magnets in the punch from one side of the line. Operation of the relay 480 will open contacts 481, thereby deenergizing relay 373 (K) and preventing the initiation of a new multiplication. The relay 480 has three other functions: one of these is to close its contacts 482 to complete a circuit to a signal lamp 483, thereby to indicate that an error has occurred in the multiplying process; a second function is to condition a circuit through a manually operable release key 484 connected to lead 321 thereby to prepare a release relay 485 for operation through a contact 486 of relay 480; the third function of the relay 480 is to complete a circuit from the lead 321 through contact 487 of relay 480 through contact 169 in the punch and a contact 488 of relay 480 to one side of the punch magnet designated 489. As is usual in punches of this type, the contact 169 is broken each time the card in the punch advances one place and, therefore, the circuit to the punch magnet will be energized repeatedly to advance the card through the punch without, however, operating any of the interposer bar magnets, the connection to which was broken at contact 479 of relay 480.

Upon operation of relay coil 480 as described, the card is passed through the punch as described, and the machine remains in this condition with the punch feed rack in its extreme left-hand position until serviced manually. At this time the card is removed, reinserted in the feed magazine or any other appropriate action taken.

Operation of release key 484 energizes relay coil 485. A locking circuit is provided for this coil to cam contact 303 (CC-4). Energization of coil 485 closes contacts 500, effecting operation of the coils 379 (LH) and 380 (PCT), to reset the product cross-adding register, the left-hand components accumulator and the unit associated with magnet 365. The product cross-adding register 7 (PCT) and the register unit associated with the CTMPR, upon their return to normal, will break the circuit from contact 475 (B-1) through relay 480, releasing relay coil 480 and returning the machine to normal.

The apparatus herein described has been adapted for checking the correctness of results

by striking out nines rather than any smaller number, for the reasons that there is less chance of the auxiliary computing means making the same mistake as the main computing means than if the threes, for example, were struck out. In certain aspects, however, the invention is not believed to be limited to the described method employed in the simplification of the problem for checking purposes, and it is intended that the apparatus and method may be varied within the scope of the appended claims, wherein the phrases "checking means," "means for checking the correctness of results" and similar language is to be interpreted to mean checking or verifying to the extent that the well-known process of "casting out nines" checks or verifies the correctness of multiplication.

What is claimed is:

1. In a calculating machine, factor entry devices, multiplying means controlled by said devices, product indicating means controlled by said multiplying means, means for casting out the nines from the factors, means for performing a multiplication involving the results obtained by casting out the nines from the factors and representing the product thereof with nines cast out, means for casting out the nines from the product transmitted to the indicating means and representing the result thereof, and means for comparing the setting of the means representing the result of the last-mentioned computation with the setting of the means representing the result of casting out the nines from the product.

2. In a computing machine, a register for receiving the digits of a factor in various denominational orders, means in said register for completing a circuit through the orders thereof to a point in a predetermined order representative of the sum of the digits of the factor minus the highest multiple of nine in the sum.

3. In a multiplying machine, register units settable to represent the digits of the factors of a problem, and checking register units settable simultaneously with the first mentioned units and operable during their setting operation to cross-add the digits set therein and cast out the nines from the result, means for performing a multiplication involving the results obtained by the checking register units with nines cast out from the product, multiplying means controlled by the first mentioned register units, means for cross-adding the digits of the product obtained by the multiplying means and automatically casting out the nines from said product, and means for comparing the cross-added product with the nines cast out with the result of the multiplication which involved the results obtained by the checking register units.

4. A mechanism for approximate checking of the correctness of multiplication performed by a multiplying mechanism comprising means for casting out the nines from the factors of prob-

lems to be performed by the multiplying machine, means for performing a multiplication involving the results obtained by casting out the nines from the factors and casting out nines from the product thereof, means for casting out the nines from the product computed by the multiplying mechanism, and means for comparing the result of the last mentioned computation with the result of casting out the nines from the product.

5. In a computing machine, means for receiving two single digital factors, and a computing means, controlled by said means for producing a single digital result indicating the multiplication of the two single digital factors minus the highest multiple of nine contained in said result.

6. In a multiplying machine, means for concurrently performing a plurality of different computations, factor receiving means for controlling the computing means, recording means, and means for comparing the results concurrently produced by the computing means to control the operation of the recording means in recording only a correct result.

7. In a computing apparatus, a cross-adding register comprising a series of register units, each unit having interconnected commutator contacts and slip rings, brushes associated with the slip rings, brushes associated with the commutator contacts and wiring interconnecting the brushes associated with the slip rings of a higher order unit to the brushes associated with the commutator contacts of the next lower order unit.

8. A cross-adding register for determining the sum of the digits of a number minus the highest multiple of nine in said sum comprising a register unit for each denominational order of the number, said unit comprising interconnected slip rings, commutator contacts and brushes associated with each ring and each contact and conductors interconnecting the brushes associated with the contacts in a lower order unit with the brushes associated with slip rings in a higher order unit.

9. In a multiplying machine having a product representing means, an apparatus for approximately checking the correctness of products computed by the machine including means for cross-adding the digits of the factors of the product computed by the machine and casting out the nines from the sums obtained, means for performing a multiplication involving the results of casting out the nines from the cross-added factors and storing same with nines cast out, means for cross-adding the digits of the products produced by the machine, and casting out nines therefrom, and means for comparing the result obtained in said storing means and said last cross-adding means.

JOHN C. GATES.
